UNITED STATES PATENT OFFICE.

MAURICE C. MEIKLE, OF NEW ORLEANS, LOUISIANA, ASSIGNOR OF ONE-HALF TO
WILLIAM WASHINGTON, OF NEW ORLEANS, LOUISIANA.

SUGAR REFINER AND SCRAPER OR UNLOADER THEREFOR.

Application filed November 21, 1921. Serial No. 516,717.

To all whom it may concern:

Be it known that I, MAURICE C. MEIKLE, a subject of Great Britain, Jamaica, B. W. I., residing at New Orleans, in the parish of Orleans and State of Louisiana, have invented certain new and useful Improvements in Sugar Refiners and Scrapers or Unloaders. Therefor, of which the following is a specification, reference being had 10 to the accompanying drawings.

In sugar refineries each centrifugal refining machine is filled and emptied individually, necessitating an operator for each machine. After the sugar is dried or refined, it has to be scraped from the sides of the basket to the bottom and discharged, and in conducting this work the attention of an operator is required at each refining machine while it is being filled, in order to prevent overloading. This makes it practically impossible for the operator to attend to more than two baskets at a time.

Therefore, the present invention has for its purpose the provision of a centrifugal refining machine, so constructed, that it is possible to so connect up a gang of machines, that a single operator can load or fill the gang in one operation without any danger of overloading the centrifugal thereby saving time and expediting the work.

Still another purpose is the provision of a discharging or scraping mechanism, so constructed that as the centrifugal basket rotates, a scraper may feed downwardly, so as to clean the sugar from the entire inner surface of the basket, and discharge it through an opening in the bottom of the basket. In this way the work of emptying the centrifugal basket is greatly facilitated.

A further purpose is the provision of a brake mechanism for the drive shaft of the centrifugal basket, for the purpose of retarding the same, when the centrifugal basket is being loaded or filled with sugar to be refined.

Additionally the invention aims to provide a rotating shaft with which the basket revolves, the shaft being mounted upon a universal joint, so that in case the shaft becomes unbalanced, the shaft is capable of lateral play or movement.

While the design and construction at

present illustrated and set forth are deemed preferable, it is obvious that as a result of a reduction of the invention to a more practical form for commercial purposes, the invention may be susceptible of changes, which are within the scope of this invention as defined in the appended claims.

The invention comprises further features 60 and combination of parts, as will be hereinafter set forth, shown in the drawings and claimed.

In the drawings:—

Figure 1 is a plan view showing a gang 65 of centrifugal sugar refining machines connected up so that all of the machines may be loaded or filled simultaneously;

Figure 2 is a side elevation of the gang 70 of centrifugal sugar refining machines, also showing their connections;

Figure 3 is a vertical sectional view 75 through the improved centrifugal sugar refining machine, showing the unloader or scraper as applied;

Figure 4 is an enlarged plan view of one 80 of the sugar refining machines, more clearly showing the details of construction;

Figure 5 is a horizontal sectional view 85 on line 5—5 of Figure 3;

Figure 6 is an enlarged detail view of a casing for the reception of the ball end of the centrifugal basket supporting shaft;

Figure 7 is also a view in elevation of the 85 casing shown in Figure 6;

Figure 8 is a detail perspective view of 90 the brake mechanism for the basket supporting shaft;

Figure 9 is a detail view of the gearing 95 between two of the shafts of the brake mechanism;

Figure 10 is a detail perspective view of one of the valves for permitting the sugar to discharge from the tank;

Figure 11 is a detail view of the means for 95 lifting the conical cover of the bottom of the centrifugal basket; and

Figure 12 is a detail perspective view of the scraper and its holder.

Referring to the drawings, 1 designates a 100 trough adapted to contain raw sugar from the sugar boiler. This trough extends over a gang of sugar refining machines. The bottom of this trough is provided with a plu-

rality of chutes 2 which extend down to a series of tanks 3. Where the chutes 2 connect with the tanks 3 openings 4 are provided. A slide 5 is mounted in guides between all of the chutes and the several tanks 3. This slide has a plurality of valves 7 corresponding in location to the location of the chutes. These valves 7 have openings 8, which, when the slide is shifted in one direction register with the openings 4, to permit the raw sugar from the trough 1 to enter the tanks 3 simultaneously. In this way the work of filling the tanks is greatly facilitated, as this can be accomplished by a single operator, and in one operation. To this end a shaft 9 is mounted in bearings 10 and 11, the former being carried by the casing of the centrifugal refining machine, while the latter are carried by the tanks 3, and is provided with a gear or pinion 12 meshing with teeth on the slide 5, so that when the shaft is rotated the slide is reciprocated, and the openings therein simultaneously caused to register with the openings 4 of the tanks 3, allowing the raw sugar to pass from the trough 1 into all of the tanks at one time.

A hand wheel 13 is carried by the shaft 9, whereby the shaft may be rotated. Each of the tanks 3 is provided with a glass or other transparent covered observation opening.

Mounted in suitable guides 14 at the intersection of the chutes or spouts 15 with the tanks is a slide 16, which is also provided with a plurality of valves 17 having openings 18, adapted to register with the chutes or spouts 15, to permit the sugar from the tanks 3 to pass through the chutes or spouts, and into the corresponding centrifugal sugar refining baskets 19. The slide 16 is provided with rack teeth 20, engaged by the pinion 21, which is mounted upon a shaft 22. This shaft 22 is mounted in bearings 23 and 24, and is provided with a hand wheel 25, whereby the slide 16 may be adjusted.

Each sugar refining machine comprises a stationary casing 26, the bottom of which is open as shown at 27 to permit the sugar to be discharged from the centrifugal basket 19. In detail the lower portion of the wall of the casing 26 is outwardly turned, and then inwardly and upwardly turned terminating in a flange 28. The upturned margin 29 of the flange 28 is provided for the purpose of preventing the syrup from overflowing as it enters the channel formed by the flange as the centrifugal basket rotates. The syrup is allowed to pass off through the pipe 30, which may be provided with a valve (not shown) for the purpose of controlling the flow.

A longitudinal beam 31 supports the basket of each centrifugal, and passing upwardly through the beams are the main hangers or supporting rods 32 for the sev-

eral centrifugals. The upper ends of these hangers 32 terminate in balls or spherical members 41, about which covers 42 of rubber or the like are provided to permit the hangers to yield laterally. Beams 33 carry the upper ends of the hangers 32, and carried from the beams are the housings 37, the bottoms of which have openings 39, for the reception of the rotating tubular shafts 40, which have annular flanges 43 in engagement with ball bearings 44. These ball bearings are supported in a raceway 45 in a plate 46, so that the tubular shaft 40 may rotate freely. The stationary supporting hangers 32 pass through the tubular hangers 40, the upper ends of shafts 40 terminating adjacent to and fitting against the lower portions of the balls or spherical members 41. Hanger bolts 34^a pass through the beams 33 and through the housing 37, and their lower ends terminate in spherical hollow casings 47. Each casing 47 consists of two semi-spherical sections 48 and 49 having flanges 50 bolted together at 51. The casings 47 enclose the covers 42, which surround the balls or spherical members 41, and in this way the stationary hangers 32 are supported, these stationary shafts 32 each supporting a centrifugal. The balls or spherical members do not rotate, and should the beams 33 become distorted or twisted or tilted the inner stationary hangers 32 will still remain vertical, and therefore the machine as a whole will automatically balance. This construction allows the shaft to rock when it is unbalanced. This happens if the amount of sugar in the centrifugal is higher on one side than on the other. It will be noted that the lower portions of the casings 47 terminate in outwardly and downwardly turned flanges 47^a, which overlie the flanges 43, and thereby protect the ball bearings 44. Arranged above the top of the housing 37 are oil cups 52, which are provided with oil conducting tubes 53, which extend downwardly and enter the flanges 47^a of the casings 47, so as to feed lubricant to the interior of the lower part of the casing. This lubricant also flows about the ball bearings 44. The plate 46 has an upstanding flange 54, to retain the lubricant and prevent it from overflowing into the interior of the housing.

Washers 35 are engaged with the upper ends of the hanger bolts 34^a, upon which are threaded the nuts 34, which support the hanger bolts in place. Where the hanger bolts merge into the casings 47, a suitable shoulder 34^b is provided, to engage the under surface of the top of the housing 37, to insure rigidity.

Mounted upon and rotatable with the tubular shaft 40 is a brake pulley or drum 55, about which a brake band 56 engages. The inner surface of the brake band is pro-

vided with a plurality of fibre or wood sections 57, which are secured to the band in any suitable manner (not shown). These fibre or wood sections bear upon the periphery of the brake pulley or drum, and thereby act to retard the tubular shaft 40 in its revoluble movement. One end of the brake band is attached at 58 to a beam 59, and connected to its other end is a rod 60, which is attached to the short arm of a bell crank lever 61, (see Figure 8) which is pivotally supported at 62 on an arm 63 of the housing 37. A cable 64 passes over a pulley 65, supported above the refining machine as shown in Figure 2 in any suitable manner, and is attached to the long arm of the bell crank lever 61. Mounted in bearings 66 below the refining machine is a horizontal shaft 67, and mounted upon one end thereof is a drum 68, about which the cable 64 is wound and is attached thereto. The other end of the shaft 67 carries a worm wheel 69, meshing with the worm 70 carried by the lower end of a shaft 71. This shaft 71 is mounted in suitable bearings 72 which are carried upon the side of the casing 26 of the refining machine, and mounted upon the upper end of the shaft 71 is a hand wheel 73. By rotating the wheel 73, motion is imparted to the shaft 67, which in turn winds the cable or cord 64 on the drum 68 sufficiently to tilt all of the levers 61, causing the shoes 57 of all the brake bands to be frictionally applied against the peripheries of the brake drums 55, thereby retarding the rotation of all of the tubular shafts 40. Thus a plurality of sugar refining machines may be connected up, so that all of them may be filled simultaneously, the cable 64 being attached to the long arm of the lever 61 of a machine at one end of the gang, and in turn connected to the levers 61 of all the machines.

Thus the entire gang of centrifugals may be retarded simultaneously to permit them to be charged.

The centrifugal basket of each sugar refining machine is supported upon and rotatable with the tubular shaft 40, and its bottom is provided with diametrically opposite openings 75, through which the sugar after being dried and refined may be discharged. The central portion of the bottom of the centrifugal basket 19 has a bearing plate 76 which is mounted upon ball bearings 77, which engage a plate 78, which in turn is also mounted upon the ball bearings 79. The ball bearings 79 engage between the plate 78 and the bearing beam 31. In this way the centrifugal basket rotates freely.

A conical cover 80 is arranged on the bottom of the centrifugal basket, so that its larger end may cover the diametrically opposite openings 75, thereby preventing the

sugar from being discharged until it is thoroughly refined and dried. It will be noted that the cover 80 fits around the tubular shaft, and its upper smaller end has an annular upstanding flange 81. A ring 82 engages around the neck of the conical cover, at a point below the upstanding flange 81, and connected to diametrically opposite portions of the ring are vertical rods 83. These rods are guided through the transverse beams 84, which are secured in any suitable manner to the inner surface of the top of the casing 26, and extend across the opening 85 of the top of the casing 26. A second ring 86 is connected to the upper ends of the rods 83, and connected to the ring are cables 87. These cables are wound upon the drums 88, which are rotatable with the shaft 9. Obviously assuming that the lower valve 17 is closed, the shaft 9 may be rotated so as to shift the slide so as to permit all the tanks 3 to be filled from the trough 1, and while this is being accomplished, the refined and dried sugar in the centrifugal basket is discharged. Therefore when the shaft 9 is rotated to open communication between the trough 1 and the tanks 3, the conical cover 80 is simultaneously raised, uncovering the openings 75 allowing the discharge of the dried and refined sugar.

Thereafter when the raw sugar enters the centrifugal basket 19, power is transmitted to the tubular shaft 40 through the medium of the pulley 89, which is keyed fast to the tubular shaft. Suitable belting (not shown) may be passed from one pulley 89 on one machine, to a corresponding pulley on an adjacent machine, and so on throughout a series thereof, so as to impart movement to all of the baskets at one time. The raw sugar solution is deposited by centrifugal force upon the perforated cylindrical side wall of the basket, where the sugar becomes refined and crystallized.

In order to remove dried and refined sugar, I provide a discharger which includes a screw 90 vertically disposed. Depending from one of the beams 84 is a bracket 91, and mounted upon both of the beams 84 is a beam 92, and mounted in bearings of the beam 92 and the horizontal arm of the bracket 91 is the screw 90. Suitable collars or nuts 93 are fast to the upper part of the screw 90, one below the beam 92 and one above it, so as to hold the screw 90 swivelly in its bearing of the beam 92. The upper end of the screw has a bevel gear 94, which meshes with a bevel gear 95 carried by a shaft 96, which is mounted in bearings 97. This shaft 96 has a hand wheel 98, by the rotation of which revoluble movement may be imparted to the screw. A scraper blade holder 99 has a cylinder 100, to which the screw 90 threads, so that when

the screw 90 is rotated in one direction or the other, the scraper blade holder 99 feeds upwardly or downwardly on the screw. The holder 99 has a channel or cavity 101 for the reception of the wood scraper blade 102, there being a set screw 103 for holding the blade in the holder. The holder has an additional cylindrical portion 104, through which a rod 105 passes. The lower end of this rod is connected in any suitable manner to a lower scraper 106, which is oscillatably mounted at 107 on the lower end of the screw. The upper end of the rod 105 has fixed thereto an arm 108, to which an arm 109 of the bell crank lever 110 is pivotally connected at 111. The bell crank lever 110 is pivoted at 112 on the top of the casing 26, and its short arm is provided with an upstanding projection 113, between the forks 114 of which, a link 115 is pivoted. This link 115 is in turn pivotally connected to a lever 116, which is pivotally mounted at 117 on one of the bearings 72. As previously stated the rod 105 passes through the holder 99, obviously the holder is permitted to move downwardly on the rod, yet the scraper is permitted to be swung laterally in either direction on the screw 90 as a fulcrum, regardless of the height of the scraper within the basket. It will be noted that the screw 90 is eccentric to the center of the basket, therefore since the scraper has a shorter radius than the radius from the center of the basket to the outer wall of the basket, the scraper will move away from the inner cylindrical surface of the wall of the basket, when the lever is tilted in one direction. When the lever 116 is tilted in the opposite direction, the scraper will move in to contact with the inner wall of the basket.

In the operation of a gang of sugar refining machines, it will be noted that the operator may rotate the shaft 9 operate the upper slide 5 and thereby open a series of valves, allowing the raw sugar solution from the trough 1 to enter the series of tanks 3. After the tanks 3 are filled, power may be transmitted to the centrifugal baskets 19, and as soon as they receive movement, the shaft 22 may be rotated, imparting longitudinal movement to the slide 16, thereby opening all of the lower valves of the several tanks 3, allowing the raw sugar solution in the tanks to enter the centrifugal baskets simultaneously. The lower valves are then closed. The centrifugal baskets rotate causing the solution to deposit upon the perforated walls of the baskets 19, the syrup draining off into the channel at the lower part of the casing 26, and when the sugar becomes thoroughly dried and refined, the baskets are stopped. However while the baskets are rotating the scraper is swung into a lateral position on the screw 90 which acts as a fulcrum, with the scraping edges

of the scrapers 102 out of contact with the walls of the baskets. Just as soon as the baskets are stopped, the operator manipulates the lever 116 to move the scraper 102 so that its edge will engage or dig into the sugar on the inner surface of the basket of possibly the first machine. The basket of the first machine is again rotated, and the dried and refined sugar is scraped from the wall of the basket. The operator, while this is being accomplished, every so often imparts movement to the wheel 98 which in turn will operate the shaft 96, and thereby rotate the screw 90, causing the scraper holder to gradually descend, until the entire inner surface of the cylindrical wall of the casing is scraped of the deposits of sugar. While the centrifugals are being scraped out the shaft 9 is rotated, so as to again operate the upper slide and open the upper valves, filling the tanks 3. When the shaft 9 is rotated, it winds up the cables 87, which lift up the ring 86 and the ring 82, thereby lifting the cover 80, uncovering the diametrically opposite openings 75. While the openings 75 are uncovered and the scraping process is being accomplished, the strip 106 tends to feed the sugar toward the center so that it can discharge through the openings, where it may be deposited in any suitable receptacles (not shown).

When the shaft 9 is rotated in the opposite direction so as to close the upper valves, the cover 80 will be lowered to again close the opening 75. Then the lower valves are opened by operating the shaft 22 and each of the baskets receives its charge from the corresponding tank 3.

It will be seen that with this construction there is a simultaneous discharge of sugar from the trough 1 into each of the tanks 3 while the several centrifugals are being cleaned or discharged, and that the act of lowering cover 80 operates the valves which control the discharge of sugar from the trough 1 into the tank 3. This gives each tank 3 its proper charge of crude sugar and then by opening all of the valves controlling the flow of sugar from the tanks to the centrifugals, the sugar will flow from the several tanks into the centrifugals or baskets at one time. It is obvious that with my mechanism all of the machines may be retarded at one time to receive the sugar from the several tanks and all of the tanks 3 may be filled at one time while the centrifugals are being operated and that all of the machines may be cleaned at one time. Thus one operator can attend to a plurality of machines with no more trouble than at the present time an operator can attend to one machine. It will likewise be noted that the suspension means which I have provided for each centrifugal is such as will permit of the baskets swinging so as to compensate

for a greater load on one side of the basket than is on the other.

While the scraping process may be conducted on each machine separately, I have 5 illustrated means whereby it may be accomplished on all of the machines simultaneously, said means consisting of bevel gears 118 upon the shaft 120, said beveled gears being in turn in mesh with the beveled gears 10 94 which actuate the screw shafts 90 of the several tanks whereby when the shaft 96 is rotated by the hand wheel 98 all of the scrapers will be fed downwardly.

The invention having been set forth, what 15 is claimed is:

1. In a centrifugal sugar refining machine, a rotatable basket having a discharge opening in its bottom, a vertically movable cover normally closing said opening, a 20 charge tank adapted to discharge into the top of said basket and having a valve controlling the discharge, a receptacle adapted to discharge into the top of the tank, a valve controlling said discharge, manually operable 25 means for permitting or preventing the discharge of material from the tank into the basket, and manually operable means movable in one direction to prevent the discharge of material from the receptacle into 30 the tank and simultaneously lowering the cover into position over the discharge openings of the basket or movable in the other direction to open communication between the tank and said receptacle and simultaneously raise said cover.

2. In a sugar refining machine, a gang of 40 rotatable baskets each open at their upper end and having a discharge opening at its lower end, a vertically movable cover disposed within the basket and normally disposed over said discharge opening, a plurality of charge tanks arranged to discharge each into a corresponding basket, a valve for each tank adapted, when shifted, to permit or prevent the discharge therefrom, a 45 single manually operable means for simultaneously controlling the discharge valves of all of the tanks, a single receptacle discharging into the several tanks, valves controlling the discharge from said receptacle, and single means for simultaneously opening all of said valves and simultaneously raising all of said covers or simultaneously closing all of said valves and closing all of 55 said covers.

3. In a sugar refining machine, a centrifugal basket having an opening in its bottom, a driving shaft for the basket passing centrally therethrough, a conical cover 60 adapted when lowered to close the opening at the bottom of the basket and when raised to uncover said opening, a tank discharging into the upper end of the tank, a manually operable valve controlling the discharge from the tank, a receptacle discharg-

ing into the upper end of the tank, a manually operable valve controlling the discharge from said receptacle and including a transversely extending, manually operable shaft, a member disposed above the basket and disposed concentric to the driving shaft, rods connected to said member and engaged with the conical cover drums on the manually operable shaft, and cables connecting said last named member and adapted to be wound upon said drums, a rotation of the shaft to wind up said cables causing the raising of the cover and the opening of the valve permitting the discharge of material from the receptacle into the tank, and a reverse rotation of the shaft lowering the cover and closing said valve.

4. In a sugar refining machine, an outer fixed casing having an inwardly extending flange at its lower end formed to provide 85 an annular syrup trough, a basket disposed within the trough and having perforated walls, a beam extending above the casing, a hanger having a nearly globular socket formed at its lower end and connected to 90 said beam, a fixed shaft having a globular head disposed within the globular socket and having free swinging movement therein, a support on the lower end of the shaft for the basket, a tubular shaft engaged with 95 the basket and surrounding the fixed shaft, means at the upper end of the tubular shaft whereby it may be rotated, and a friction brake engageable with the upper end of the tubular shaft.

5. In a sugar refining machine, a rotatable basket having a discharge opening in its bottom and perforated walls, an outer casing within which the basket rotates, means for rotating the basket, means for 105 retarding the rotational movement of the basket, means for scraping the sugar collected on said walls and causing its discharge comprising a screw passing vertically downward into the basket, a scraper on the lower end of the screw mounted for oscillating movement therearound, the scraper having screw-threaded engagement with the screw for vertical movement and having rotational movement around the screw, the scraper being adapted, when shifted in one direction, to contact with the wall of the basket, means for rotating the scrapers around the screw comprising a vertical rod engaging both scrapers and extending out through the top of the basket, a lever, operating means connected to said lever for shifting said rod in an arc of which the screw is the center, and means for manually rotating said screw.

6. In an apparatus for refining sugar, a plurality of rotatable baskets each open at its upper end, a trough common to all of said baskets, a plurality of measuring tanks disposed between the trough and said bas-

baskets therein, a measuring tank for each basket, single means for controlling the passage of material from the trough into the tanks, single means for controlling the passage of the material from the tanks into the baskets, means common to all of said baskets for rotating the baskets, means for simultaneously controlling the rotational

speed of the baskets, scraping means for each basket, and single means for controlling the scraping means of all of the baskets. 10

In testimony whereof I hereunto affix my signature.

MAURICE C. MEIKLE.
